UNITED STATES PATENT OFFICE.

CHARLES M. ALLEN, OF BUTTE, MONTANA.

CONVERTER.

SPECIFICATION forming part of Letters Patent No. 519,219, dated May 1, 1894.

Application filed April 18, 1893. Serial No. 470,827. (No model.)

To all whom it may concern:

Be it known that I, CHARLES M. ALLEN, a citizen of the United States, residing at Butte city, Montana, have invented certain new and 5 useful Improvements in Converters for Smelting Ores, of which the following is a specification.

In the drawings, Figure 1 is a side elevation of my improved converter; Fig. 2 a transverse section taken in line 2 of Fig. 1; Fig. 3 an end view of the converter, detached, and rotated into position for discharge; and Fig. 4 a section showing the arrangement of the side and end water jackets.

15 In making my improved converter, I make a cylinder, A, of the desired length and diameter. This cylinder is closed by ends B. The sides and ends of the converter or converting chamber are formed of sheets of metal, 20 so as to form a water space, C, between the sheets to permit the circulation of water to preserve the converting chamber from destruction by the intense heat. The inner sheets of the side and end water jackets are turned out, as at a, to permit the edges to be riveted or otherwise fastened to the edges of the outer sheets so as to obviate the necessity 25 of making rivet or other holes through the inner sheets, and thus avoid liability to accident which would be occasioned were there a 30 possibility of water leaking into the converting chamber.

While I have spoken of the converting chamber as being a cylinder, yet it is to be understood that the edges are not closed together, so that there is an opening, b, for the admission of the material to be treated into the converting chamber, as well as to afford an exit 35 for the smoke, dust and fumes resulting from the operation of the converter. I arrange, in one or both ends of the converter, a section D, 40 formed of brick work or other frangible material, which can be punctured to form a tap to draw off the material from time to time, as desired. I also provide a row of tuyeres E, 45 entering the converter, preferably at the bottom, when in working position, through which a blast of air will be driven as necessary in operation. In the working position of the 50 converter, the section, D, in the end or ends,

is above the surface of the molten material, and the tuyeres enter below the surface of such material. When, however, the converter is rotated to permit a portion of the molten material to be turned off, the position of these 55 parts is reversed and the tuyeres enter above the molten material, and the sections of frangible material are below the surface of the molten matter, so that when they are punctured, a desired quantity may be turned off. 60

I arrange a hood, F, over the converter, to carry off fumes, and provide a chute, G, through which the ore to be treated may be introduced. The converter rests upon rolls, H, and in order to rotate it, I provide around 65 its outer surface a row of teeth I, which engage with the teeth of a gear wheel, J, which may be rotated by a band on a pulley, not shown, on the shaft j, or in any other desired manner, so that from time to time, as desired, the rotating chamber may be rotated enough to bring it into its discharge position, and, after a desired quantity of material has been turned off, rotated back into its working position. I might say that it is intended 70 in operation to leave a portion of the molten material in the converting chamber to assist in the ignition and melting of the succeeding charge of new or raw material, so that the operation may be continuous and not interrupted. 75 For the reduction of the first charge, it will, of course, require fuel, as is usual in such instances. It will also be understood that it is expected that there will be sufficient sulphur in the ores treated to supply the requisite amount of fuel for their reduction, after 80 the first charge has been smelted. 85

I claim—

1. A rotatable converter having a cylindrical converting chamber for holding molten material, tuyeres in the cylindrical portion for the admission of an air blast, a section D, of brickwork in the end of the converter adapted to form a tap, and means for rotating the converter, substantially as described. 90
2. In a converter, the combination of a cylindrical converting chamber having side and end water jackets composed of metal sheets with the edges of the inner sheets bent outwardly to overlap the edges of the outer sheets 100

to which they are fastened, whereby rivet and other holes in the inner sheets are avoided, and end sections adapted to be punctured or broken to form a tap, substantially as described.

- 5 3. In a converter, a cylindrical converting chamber having its sides water-jacketed in

combination with truncated cone-shaped wa-
ter-jacketed ends, substantially as described.

CHARLES M. ALLEN.
